GEORGE W. MARTIN, OF BOSTON, MASSACHUSETTS.

Letters Patent No. 85,748, dated January 12, 1869; antedated January 6, 1869.

IMPROVED HEEL FOR BOOTS AND SHOES.

The Schedule referred to in these Letters Patent and making part of the same.

To whom it may concern:

Be it known that I, GEORGE W. MARTIN, of the city of Boston, in the county of Suffolk, and State of Massachusetts, have, as I believe, invented new and useful Improvements in Detachable Heels for Boots and Shoes; and I do hereby declare the following to be a full and exact description of the same, reference being had to the drawings that accompany and form a part of these specifications, in which—

Figure 1 is a perspective view of a heel entire.

Figure 2, the two parts of the heel separated, showing screw and socket.

Figure 3, sectional view cut on line 1-2, showing cross-section of the heel-plate also.

Figure 4, modification of the screw-parts for fastening.

Figure 5, section on line 3-4.

Figure 6, section on line 5-6, and illustrates the method of attaching the plate *v*.

Letter *A* represents the base of a boot or shoe-heel.

Letter *B*, detachable part of a boot or shoe-heel.

Letter *c*, heel-plate.

Letter *d*, a spindle, with screw-threads.

Letter *e*, socket, with female screw, to receive spindle *d*.

Letter *f*, a convex projection on the outer end of the spindle *d*.

Letter *g*, a slight depression or concavity in the bottom of the socket *e*.

In fig. 4, I have illustrated a modification of the method of fastening the two parts *A* and *B* together.

Letter *h* is a hollow spindle, and has screw-threads on both the inside and outside.

Letter *i*, the socket for *h*, and provided with screw-thread.

Letter *j*, a spindle rising from the bottom of the socket *i*, and, in diameter, corresponding to the opening *p* in the spindle *h*. This will be of elastic material, in length a little more than the depth of the opening *p*, and may be threaded, if thought desirable.

The metallic plates *u v* may be attached and secured to the parts *A* and *B*, either by screws, as 1, 2, 3, 4, or by having the openings 5, 6, 7, 8, formed as in fig. 6, with the same material of which the heel-piece is formed, filling them, and these plates made still more secure by the flanges *x x*, also illustrated in fig. 6.

The heel-plate *c* is secured in the same way, as may be seen in fig. 3.

This invention provides for the interchange of the heel-pieces *B* from right to left, or "vice versa," when uneven wear thereof renders it desirable, and, as there may be a variety of patterns of *B*, yet all corresponding on the attaching-surface to *A*, any one can suit the taste as to height of heel or the width of the wearing-face thereof. Still further, the parts *B* may be made with more fulness on one side than on the

opposite, for the advantage of those who are prone to wear much more on one side than the other, or to turn the ankles either in or out.

In putting together the two parts *A* and *B*, fig. 2, the projection *f* will meet the opposing surface of *g* before the two opposing surfaces *O O* have come in contact; consequently, as the piece *B* is further turned and the screw *d* further advanced into the socket *e*, much pressure will be produced, not only at *g*, but also on the threads of *d* and *e*, so that the force required to turn *B* either forward or backward at this juncture will afford ample security for keeping the part *B* in place after once being brought to position, as in fig. 1.

In turning the two parts *A'* and *B'* together, the spindle *j* will reach and press upon the bottom of the opening *p* before the two opposing surfaces *O'* and *O'* have met each other. (See fig. 5 of drawings.)

Now, as the spindle *h* is further turned into the socket *i*, pressure and friction will result both in the opening *p*, and between the threads of the spindle *h* and the socket *i*, sufficient to retain the removable heel-piece *B* in place, and prevent it from being turned to the right or left by any concussion it would be likely to receive while in wear.

If these heel-pieces *A* and *B* are made of elastic material wholly, such as rubber or the like, or of any plastic material, they would be formed by moulding and the threads upon *d* and *e* formed in the same way, and at the same time, and of the same piece and material.

The part *A* may be made of leather, or any suitable firm material, as, for instance, wood, and the screw-thread formed in any manner suitable to the nature of the material used. Or, if desirable, portions only of either *A* or *B* may be of elastic material, such as the spindle *d* and socket *e*, and such additional portions of the body of the same as will suffice to form a desirable union with the other parts of these same *A*, *B*, which "other parts" may be of wood, leather, or any other suitable material.

In attaching the plate *v* to the heel, as already illustrated, the process is by moulding the said plate with the part of the heel it contacts with, the material being pressed forcibly into the openings 5, 6, 7, 8, which are not only larger at the outside, but have threads cut on their surface, as may be seen at *z z* in fig. 6.

In the same manner is the plate *c* moulded in with its contacting parts, and held in the same way.

The flange *x* is applied as an auxiliary to the above in holding in place the plate *v* or the heel-plate *c*.

This method saves all screws and nails.

What I claim as my invention, and desire to secure by Letters Patent, is—

1. An elastic boot or shoe-heel, when formed of the two parts *A* and *B*, one provided with screw-spindle *d*, the other with screw-socket *e*, the threads of each being formed by moulding at the same time and of the same

material as the body of the part to which they belong, and provided, the one with the projection *f*, the other with the depression *g*, to operate as described.

2. The part *B*, when its screw-spindle *d* is provided with the projection *f*, and made of elastic material, and the main body-part thereof of non-elastic material, for the purposes described and set forth.

3. A boot or shoe-heel, with its two parts *A* and *B* united by means of the two screw-spindles *h* and *j*, and the two corresponding sockets *i* and *p*, as specified, when

arranged to operate as described and for the purposes set forth.

4. The manner of attaching the plate *v*, as shown in fig. 6, as also the plate *c*, shown in figs. 1 and 3.

In testimony whereof, I have signed my name to this specification, in the presence of two subscribing witnesses.

GEO. W. MARTIN.
